(Cl. D48—32)

To all whom it may concern:

Be it known that I, Robert W. Garrett, a citizen of the United States, residing at Washington, in the District of Columbia, have invented a new, original, and ornamental Design for a Taxicab Cruising Lamp, of which the following is a specification, reference being had to the accompanying drawing, forming part thereof.

Figure 1 is a perspective view of a taxicab cruising lamp, showing my new design;

Figure 2 is a side elevational view thereof;
Figure 3 is a front elevational view, and
Figure 4 is a top plan view of the same.

I claim:
The ornamental design for a taxicab cruising lamp, as shown.

ROBERT W. GARRETT.
